UNITED STATES PATENT OFFICE.

FRANK V. GAY AND ARTHUR A. WIXOM, OF CLAY CENTRE, KANSAS.

DOOR-CHECK.

SPECIFICATION forming part of Letters Patent No. 416,056, dated November 26, 1889.

Application filed June 5, 1889. Serial No. 313,200. (No model.)

To all whom it may concern:

Be it known that we, FRANK V. GAY and ARTHUR A. WIXOM, citizens of the United States, residing at Clay Centre, in the county 5 of Clay and State of Kansas, have invented a new and useful Door-Check, of which the following is a specification.

This invention relates to door-checks; and it has for its object to provide a device of this 10 class which shall be simple in construction, efficient, and comparatively noiseless in operation, in which the retaining-springs may be adjusted at any desired angle, and in which the tension of the said retaining-springs may 15 be conveniently regulated.

The invention consists in the improved construction, arrangement, and combination of parts which will be hereinafter fully described, and particularly pointed out in the claims.

20 In the drawings hereto annexed, Figure 1 is a perspective view showing our improved door-check applied in position for operation. Fig. 2 is a longitudinal sectional view. Fig. 3 is a plan view. Fig. 4 is a bottom plan. 25 Fig. 5 is a perspective view illustrating the parts constituting our invention separated or detached from each other.

The same letters refer to the same parts in all the figures.

30 A designates a shank or stem provided at its inner end with a screw-threaded extension B, by means of which it may be attached to the wall or wash-board of a room in operative position, as shown in Fig. 1 of the drawings. 35 If desired, the screw-threaded extension might project downwardly to enable the device to be attached to the floor of a room without departing from the spirit of our invention. The outer end of the shank A is 40 provided with an approximately circular horizontal plate C, to which a pair of leaf-springs D D are connected by means of a central pivotal bolt E. The said leaf-springs, which are arranged, respectively, on the upper and under sides of the plate C, are provided at their 45 outer ends with coils or rolls F F, facing each other, and adapted to clamp and hold the door-button between them, as will be presently more fully described. The horizontal 50 plate C is provided near its inner end with a segmental slot G, which is concentric with the

pivoting-bolt E. Through the said slot and through perforations H in the inner ends of the leaf-springs D extends a bolt I, which also serves to connect a pair of tension-springs J J to the outer ends of the leaf-springs D D. The said tension-springs are provided at their inner ends with perforations K to admit of the passage of the bolt I. They also are provided with perforations L for the passage of the pivotal bolt E, and between the said perforations K and L they are provided with shoulders M. It will be seen that the leaf-springs D and tension-springs J may be swung upon the pivotal bolt E to any 65 desired angle with relation to the stem or shank K, and they may be secured in any position to which they may be adjusted by means of the bolt I, which works in the segmental slot G. The ends of the bolts E and I are provided with nuts, designated, respectively, by letters N and O. The said nuts are square, and their sides abut against each other so that the said nuts shall keep each other locked. The heads of the bolts are provided with notches P to enable them to be adjusted by means of an ordinary screw-driver. It will be seen that the pressure of the tension-springs J upon the leaf-springs or retaining-springs D D may be regulated by prop- 75 erly adjusting the bolt E.

Q designates the door-button, which is composed of a screw-threaded shank R, having an integral head S, provided on its inner side with an annular flange W, over which the 85 button T, which is made of hard rubber, is molded. It will be seen that by this construction the button is secured very rigidly to the screw-threaded stem, and is not liable to become detached when the said button in 90 operation is disengaged from the retaining-springs. The button is constructed with a head T, which is rounded and adapted to enter between the coils or rolls F F at the outer ends of the retaining-springs, and shoulders U U, adapted to abut against the said 95 coils or rolls.

The operation of the invention and its advantages will be readily understood from the foregoing description taken in connection 100 with the drawings hereto annexed. The door-check and the button are attached in suitable

- positions, respectively, to the wall of the room and to the door, and the retaining-springs are then adjusted at any suitable angle at which they will most readily be engaged by the door-button. When the door is swung open, the head T of the button will enter between the outer ends of the retaining-springs, which will clutch and hold the said head T and prevent the door from being accidentally shut. 5 When it is desired to shut the door, the head T of the button may be disengaged from the retaining-springs by pulling the door with the requisite degree of force. The tension of the retaining-springs may be regulated by loosening or tightening the bolt E, thus causing the tension-springs J J to bear upon the said retaining-springs with a greater or less degree of pressure. 10 15

The construction of the device is simple and inexpensive, and it may be manufactured at a small expense. 20

Having thus described our invention, what we claim, and desire to secure by Letters Patent, is—

- 25 1. In a door-check, the combination, with a shank having a rearwardly-extending screw-threaded extremity and a horizontal centrally-perforated plate provided with a segmental slot in rear of and concentric with said perforation, of the leaf-springs mounted pivotally upon a bolt extending through the central

perforation and having rolls or coils at their outer ends, the tension-springs secured by said central pivotal bolt to the outer sides of the leaf-springs, connected by a bolt extending through the leaf-springs and through the segmental slot and having shoulders formed intermediately between the said pivotal and connecting bolts, and the door-button formed with a head adapted to engage the rolls or coils at the outer ends of the leaf-springs, substantially as and for the purpose set forth. 35 40

2. In a door-check, the combination of a horizontal plate having a segmental slot, the retaining-springs connected pivotally to the upper and under sides of the said horizontal plate, the tension-springs mounted upon the pivotal bolt, the tightening-bolt extending through the segmental slot and connecting the inner ends of the retaining-springs and the tension-springs, and the nuts having flat sides abutting against and locking each other, substantially as and for the purpose set forth. 45 50

In testimony that we claim the foregoing as our own we have hereto affixed our signatures in presence of two witnesses. 55
